UNITED STATES PATENT OFFICE.

ORSON N. KELLY, OF LOS ANGELES, CALIFORNIA.

VENDING MACHINE.

Application filed November 13, 1926. Serial No. 148,197.

This invention relates to vending machines and more particularly to such a machine, in which a plurality of stacks of packages or articles are delivered successively by a coin operated mechanism.

The object of the invention is to produce a coin controlled vending machine occupying comparatively small space but having a maximum capacity. A further object of the invention is to provide a coin operated vending machine by means of which a plurality of stacks or articles or packages may be delivered, the rear stack being delivered before the delivery of the front stack, leaving the front stack on display while the delivery of the rear stack is being made. Another object is the provision of a coin controlled mechanism embodying a plurality of ejectors, which are designed to act upon different stacks of articles. A further object is the provision of novel controls against reverse movement of a coin control mechanism. A still further object is the provision of means for insuring return of coin from the machine when it does not operate, and for providing for the refusal of slugs in the operation of the machine. A still further object is the provision of means for locking the coin control mechanism and for returning the coin when the machine is empty.

Among the objects are simplicity of construction, inexpensiveness and a practically fool-proof machine, and one which will give continuous service with little attention. Other objects and advantages of the invention will hereinafter appear in the following description and the novel features thereof will be particularly pointed out in the appended claims.

Like letters of reference indicate like parts throughout the several figures of the drawings, in which

Figure 1 is a section through the vending machine with an empty rear compartment,

Figure 2 is an elevation of the back of the machine detached and with a part of the back plate broken away,

Figure 3 is a rear elevation of a lower portion of the machine with the back removed and with no articles in the machine,

Figure 4 is a section taken on the line 4-4 of Figure 1,

Figure 5 is a section taken on the line 5-5 of Figure 1, and

Figures 6 to 11 are details.

The vending machine consists of a casing 10 having therein a plurality of stacks of articles for delivery, the stacks occupying the relative positions of front and rear to each other. Beneath the commodity compartment of the casing is a coin controlling operating mechanism designed for accomplishing the delivery of articles from all of the stacks. The casing back carries the coin entrance chute as well as the coin delivery chute. These parts will now be described in detail and their conjoint relationship pointed out. In the drawings, there is illustrated a casing embodying four stacks of packages or articles, but it will be appreciated that the parts are duplicated in the right and left compartments.

The casing 10 comprises a front commodity compartment 11, a rear commodity compartment 12, a coin control mechanism compartment 13 and a delivery compartment 14. The compartments 11 and 12 are filled with stacks of articles to be delivered upon the insertion of a coin in the machine upon the operation of a pull rod. The bottom 15 of these compartments is suitably slotted at 16 (see Figure 4) for the projection thereabove of a pair of ejectors designed to eject articles from the machine, and suitably notched at 18 to permit one of the ejectors to fall into an inactive position at the end of its travel. At the front of the compartment 11 there is a guard 19 designed to hold an article in the compartment but to be moved forward when the article is to be delivered.

The back 20 of the casing is provided with a plate 21, attached thereto by lugs and screws 22, and forms the rear wall of the rear commodity compartments. Attached to the back are coin chutes 23 into which the coin is dropped by means of the slot 24. One wall of the chute is provided with a cutaway portion 25 and a boss 26 to eliminate coins smaller than required. At the lower end of the back are delivery chutes 27 designed to receive coins directly from the chute 23 when the rear ejector is out of the path of the coins, and also to receive coin from the rear ejector when the said

ejector is locked against movement, and to receive slugs too light to actuate the ejector. It will be appreciated that when the back is upon the casing and a coin falls within the 5 chute 27, it will be delivered from the machine through the coin return cup 28 on the outside of the casing. The plate 21 at its lower edges is provided with suitable notches 29 to permit the ejector to move forward 10 after the coin has tilted it.

Beneath the bottom plate 15 a carrier 30 (see Fig. 5) is slidably mounted within the casing. This carrier is shown as formed of a single piece of heavy stock wire in rectangular 15 form with an extension forward to constitute a pull rod 31, having a knob 32. On the rear portion 33 of the carrier is formed a support 34 for the pivoted ejector 35. This ejector comprises a coin pocket 36 20 at one end, lying normally in the path of the coin 37 as it descends the chute 23. The opposite end of the ejector constitutes a commodity engaging head 38, which is provided with a lip 39 to ride upon the edge of the 25 slot 16 in the bottom plate 15. On the support 34 is a loop 40, which limits the movements of the ejector and reinforces its pivot 41.

The ejector is shown in Figure 6 in full 30 lines in normal position to receive a coin from the chute 23. If such coin is of proper weight, it will operate the ejector to a position shown in dotted lines when the head 38 will be raised above the level of the bottom 35 15. In the position shown in full lines, the pocket 36 has an inclined bottom 42, which will direct a light weight slug or coin into the chute 27 and also direct any full weight coin into said chute when it fails to trip.

40 Mounted on the forward portion of the carrier 30 is a support 42, to which is pivoted at 45 a supplemental ejector 43 comprising a head 44 and a counterbalance 46.

The active position of the supplemental 45 ejector is shown in full lines in Figure 8 while its dotted line position indicates its position when an article rests upon the bottom 15 above the ejector, forcing the head 44 through the slot 16. This supplemental 50 ejector is free to assume its full line position whenever no article presses upon its head, and its movements are limited by the stop pin 47 and by the counterbalance 46 against the under surface of the bottom 15.

55 The mechanism chamber 13 contains a partition 48 and a standard 49. The partition 48 (see Figure 6) holds the coin in the pocket 36 after the ejector has been actuated by the coin. As the carrier 30 advances toward the front of the machine upon a pull upon the knob 32, the head 38 will ride upon the edge of the slot 16 in plate 15, and will be held elevated in this position until it reaches the notch 18 in the plate 60 15. At the same time the coin is maintained

in the pocket 36 by the partition 48 until it reaches the cutaway portion of the partition at 50', at which time it will be permitted to fall into the chamber 13, and the ejector will then assume the position where the head 38 drops below the plate 15. This is accomplished by the weight of the head assisted by having the pocket ride upon an incline 51, which is part of the partition 48. On the partition 48 may be placed notches 52 75 to engage the coin and prevent backward movement of the carrier when the coin is in the pocket.

As shown in Figure 6, the standard 49 will prevent the forward movement of the 80 carrier, because of the engagement of the head 38 with the rear face of the standard. When, however, the ejector is actuated, the head rises above the standard 49, and may be moved forward. After completing its 85 forward movement, the carrier is returned to normal position by means of a spring 53 attached at one end to the forward portion of the carrier and at the other to a pin 54 on the standard. The upper edge of the 90 standard is provided with notches 50, with which the head of the ejector engages in its rearward travel, said notches preventing the return movement forward of the carrier.

The package guard 19, which closes the 95 forward compartment, is mounted upon the pull rod 31 and moves from the front compartment as the rod is pulled forward. In order to prevent the securing of an article when the guard 19 is away from the front 100 compartment, a supplemental guard 55 is pivotally mounted upon the under surface of the plate 15 and has its forward portion flanged and adapted to rise within the slot 16 in advance of an article in the front compartment, at the time the pull rod is actuated. The forward portion of the carrier in its movement forward will cause the supplemental guard to come into guarding position. As the carrier moves backward, 110 the guard will drop and is limited in its downward movement by the heel 56.

Means are provided for insuring the return of a coin when the machine is empty. For this purpose a lock is provided for the 115 ejector 35, consisting of a projecting end 56 of a rod 57, which is adapted to be extended into the path of the head 38 of the ejector, as shown in Figure 10. The rod is mounted in bearings upon the under surface of the 120 bottom 15, and normally lies with a forward bent end within the plain of the bottom 15, as shown in Figure 11, a slot 59 being in the bottom 15 below the front commodity compartment. Between its ends the rod is provided with a weight 60 acting as a counterbalance causing the wire to turn in its bearings and the front end to project above the bottom 15. The rear bearing is provided with a cam groove in which travels a pin on 130

the rod 57. It will be appreciated that when there is a package or article in the front compartment, the bent end 58 will be depressed against the action of the weight 60, and in 5 this condition the projecting end 56 will be out of the path of the head 38 of the ejector, and that when the last package or article is removed from the front compartment, the weight 60 will cause the bent end to project 10 above the bottom 15, and through the bearing 61 with its cam groove and pin connection with the rod, will cause the rod to bodily move backward so that its end will project 15 into the path of the head 38 and lock it against actuation. In that event, if a coin is dropped into the machine, it will fail to operate the ejector and will be returned through the chute 27.

The operation of the machine is as follows: 20 Articles or packages are stacked in both the front and rear commodity compartments. A coin is inserted in the slot 24 and falls within the pocket 36 of the ejector 35, which depresses that end of the ejector and raises 25 the head 38 thereof into a position where the lip 39 engages the edge of the slot 16 of the bottom 15. This head is then directly behind one of the packages 62 in the rear compartment. Upon a pull upon the rod 32, the 30 ejector as shown in Figure 7 will advance the package 62 and at the same time the package 63 in front of it, which was the lowermost package in the front stack. During this operation the guard 19 has been 35 advanced so that the package 63 may fall upon the incline 64 and be delivered from the compartment 14 of the machine. At the time of the delivery of the package 63, the package 62 will have advanced to occupy the lowermost position in the front stack, taking 40 the place of the package 63. The supplemental guard has been lifted by the carrier to prevent the package 62 from being removed from the machine while the rod is 45 in advanced position.

In the detail description of the coin control mechanism, it has been made clear how the forward travel of the carrier parts is accomplished, and how reverse movement thereof 50 is accomplished while travelling forward by the coin coacting with the notches 52, and how reverse movement thereof is accomplished while travelling backward by the stops 50 on the standard 49.

55 As soon as package 62 has advanced sufficiently to permit it, the remaining packages in the rear compartment will fall and each in its turn will rest upon the bottom 15. It will be appreciated that the operation just 60 described in connection with the delivery of the package is repeated so that all of the packages in the rear compartment are advanced in their turn to occupy the lowermost position in the front compartment, 65 pushing the preceding package into delivery.

As long as packages remain in the rear compartment, the supplemental ejector 43 will lie inactive below the bottom 15. As indicated in Figure 1, however, when the packages have all been removed from the 70 rear compartment, this supplemental ejector will rise and occupy a position behind the lowermost package in the front compartment. As it moves with the carrier 30, subsequent advance movements of the carrier 75 will cause the ejector 43 to push from the machine the lowermost package in the front compartment.

It will be appreciated that the operation 80 of the machine is still under the control of the ejector 35, and that the forward movement of the carrier is dependent upon the reception of coin in the pocket 36 of the ejector. The supplemental ejector upon the delivery 85 of a package is forced into inactive position, shown in dotted lines in Figure 8, by the weight of the package falling upon it. This ejector then returns under the bottom 15 to the point where there is no longer any weight above it, when it assumes the position shown 90 in Figure 1 and by full lines in Figure 8. It will be noted that the ejector 43 has a rearwardly extending ear, well within the path of the falling package, so that the package is 95 certain to depress it.

It will be obvious that the supplemental ejector is idle so long as there are packages in the rear compartment, but when there are packages in the front compartment only, this ejector is employed to eject them. 100

By the employment of front and rear stacks of packages, and delivering them in the manner set forth, there is always a display of the packages in the front compartment just as long as there are packages in 105 the machine. The rear compartment is first exhausted before delivery is made of packages from the front compartment.

It will be appreciated that the details of 110 construction shown and described are merely indicative and that the invention may be embodied in other forms within the scope of the appended claims.

Having described the invention, what is 115 claimed is:

1. A machine comprising a commodity chamber containing front and rear stacks of articles, and a coin controlled device for delivering said articles comprising means for advancing an article from the rear stack to the front stack at the same time that an article from the front stack is being delivered and means active only after the rear stack is empty for delivering articles from 120 the front stack.

125 2. In a vending machine, a coin controlled mechanism for multiple stacks of articles to be dispensed comprising a carrier adapted to become operative upon the insertion of a coin, a pusher for advancing an article from 130

one stack to another and for delivering an article from one stack, and a supplemental pusher for delivering an article after one stack has become exhausted.

5 3. A vending machine comprising front and rear compartments for articles, a slideable carrier operating under said compartments, a pull rod for moving the carrier, an ejector attached to the rear of the carrier 10 comprising a coin receiving end and a commodity engaging end, the commodity engaging end being adapted to abut against the lowermost article in the rear compartment, and a supplemental ejector on the forward 15 portion of the carrier having a commodity engaging head adapted to normally lie under the compartments and adapted to rise into the rear compartment and to abut against a commodity in the front compartment when 20 there is no commodity in the rear compartment, the forward movement of the carrier and ejectors being dependent upon a coin being received to actuate the rear ejector.

4. In a vending machine containing front 25 and rear stacks of articles to be dispensed, a coin controlled delivering mechanism comprising a sliding carrier, an ejector mounted upon the rear of said carrier and adapted to be tripped into active position upon the 30 insertion of a coin to eject articles from the machine, and a supplemental ejector on the forward portion of the carrier operable to eject articles from the machine when one of the stacks is empty.

35 5. The machine of claim 4, wherein the ejector on the carrier is provided with a pocket for the coin and stops are provided on the machine to cooperate with the coin to prevent reverse movement of the carrier 40 when the coin is in the pocket.

6. In a vending machine comprising a commodity chamber containing front and rear compartments, a coin controlled mechanism mounted below said chamber and 45 comprising a pivoted ejector having a commodity engaging head adapted to project into the commodity chamber to advance the commodity and to drop below the commodity chamber in its return to normal position, 50 and means below the commodity chamber for engaging said head to prevent forward movement of the ejector during its return to normal position.

7. In a vending machine having a commodity chamber, a coin controlled mechanism having an ejector actuated by the insertion of a coin, means for locking said ejector against movement when no articles are present in the commodity chamber, said 60 means comprising an element of which one end projects into the commodity chamber and the other end of which projects into the path of the ejector.

8. In a vending machine, a casing, a chute

for the admission of coin and a delivery chute for the return of coin, a coin controlled device comprising a tiltable ejector provided with a pocket, said pocket normally lying in the path of the admission chute and discharging into the delivery chute when in 65 untilted position, said admission chute discharging directly into the delivery chute when the tiltable element is removed from the path of the coin.

9. The machine specified in claim 8 wherein the tiltable element is counterbalanced to operate and retain a coin of proper weight or to fail to operate and dump a coin of lighter weight into the delivery chute.

10. The machine specified in claim 8 80 wherein means are employed for locking the ejector against tilting when there are no articles left in the casing.

11. In a device of the character described, front and rear commodity chambers for 85 stacked articles, a carrier, an ejector mounted on the carrier and formed at one end with a coin receiving member and with a commodity engaging member at the opposite end, and a supplemental ejector mounted 90 on said carrier and adapted to engage an article which is not in position to be engaged by the coin receiving ejector.

12. A coin controlled vending machine comprising front and rear commodity chambers, a slideable carrier under said chambers, pivoted ejectors attached to the carrier for emptying first the rear chamber and afterwards the front chamber, one of said ejectors adapted to be tilted by an inserted coin, 95 means coacting with said coin operated ejector for locking said carrier against movement but permitting said movement when said ejector is tilted, means for advancing and returning the carrier, means for returning the coin when the coin operated ejector fails to tilt, and means for locking the coin operated ejector against tilting when the machine is empty.

13. In a vending machine, a casing having a bottom upon which front and rear stacks of articles are adapted to rest, a coin controlled discharge carrier, means on the carrier for discharging the lowermost article in the front stack and for advancing the 115 lowermost article of the rear stack, and additional means for delivering the lowermost article of the front stack when the rear stack is exhausted.

14. A vending machine comprising in combination a compartment for front and rear stacks of articles, means operable upon the introduction of a coin for dispensing said articles comprising a plurality of ejectors, one of said ejectors being adapted to advance 120 an article from the rear stack to the front stack and at the same time deliver an article from the front stack, and the other of said 125

ejectors adapted to deliver articles from the front stack when there are no articles in the rear stack.

15. A machine comprising a compartment containing articles in stacked relationship, a coin controlled mechanism for delivering said articles comprising a pivoted lever adapted to be tilted into active position upon the insertion of a coin to eject articles from 10 the machine, a coin return chute, said lever being so formed as to direct the coin into the coin return chute when said lever fails to tilt.

16. A machine comprising a housing containing articles to be dispensed, a coin receiving chute, a coin return chute, and 15 an ejector mounted in the path of the coin receiving chute and tilttable by the inserted coin to unlock the delivery mechanism for delivering articles from the machine and adapted upon the failure to tilt, to direct the coin to the return chute.

17. A coin controlled machine comprising a casing having a plurality of stacks of articles, means adapted to dispense the bottommost article of one stack by abutting against it the bottommost article of the next stack, and additional means adapted to dispense the remaining articles in the machine after one of the stacks has been depleted, and means to 30 prevent operation of the machine by spurious coins of insufficient size or weight.

18. A vending machine comprising in combination front and rear stacks of articles, a pivoted ejector responsive to the weight of 35 a coin for emptying the rear stack and for also dispensing the lowermost article in the

front stack until the rear stack has been depleted, and means for then dispensing the articles in the front stack, and means for shifting the pivoted ejector as it reaches its 40 forward position.

19. In a device of the character described, front and rear commodity chambers for articles to be vended, a carrier, a pivoted lever mounted on the carrier and formed at one 45 end with a coin receiving member and with a commodity engaging member at the other end, and a supplemental lever adapted to engage an article which is not in a position to be engaged by the coin receiving lever. 50

20. The machine of claim 19 where the pivoted lever on the carrier is provided with a pocket for the coin and stops are provided to cooperate with the coin to prevent reverse movement of the carrier when the coin is in 55 the pocket.

21. A coin controlled vending machine comprising a chamber for commodities to be dispensed, a slidable carrier under said chamber, a pivoted ejector attached to the carrier for emptying the chamber, said ejector adapted to be tilted by an inserted coin, means coacting with said coin operated ejector for locking said carrier against movement but permitting said movement when 60 said ejector is tilted, means for returning the coin when the coin operated ejector fails to tilt, and means for locking the ejector against tilting when the machine is empty. 65

In testimony whereof I affix my signature.

ORSON N. KELLY.
